Inventor:
Walter J. McClelland,
Baker & Co
Atty's.

UNITED STATES PATENT OFFICE.

WALTER J. McCLELLAND, OF EAST ORANGE, NEW JERSEY.

STOCKING.

Application filed April 20, 1925. Serial No. 24,536.

To all whom it may concern:

Be it known that I, WALTER J. McCLELLAND, a citizen of the United States, residing at East Orange, in the county of Essex and State of New Jersey, have invented new and useful Improvements in Stockings, of which the following is a specification.

This invention relates to stockings or hose, and particularly to stockings of the turned down or top cuff type. It will be recognized, however, that in many of its aspects, the invention is not limited to stockings of that particular type, but is generally applicable to stockings of various types.

In the manufacture of stockings of the turned down or top cuff type, considerable difficulty has been heretofore encountered in making the cuff so that it will retain its initial form and at the same time possess sufficient elasticity to grip the leg of the wearer and hold the stocking in proper position thereon. This difficulty is increased from a practical and commercial standpoint by limitations imposed by style and customs upon the selection of stocking materials, and also by problems arising in the successful dyeing of the stockings. Ordinarily, the complete stocking, including the cuff, is formed from silk or similar material which is pleasing to the eye and comfortable to the wearer. The stocking is knitted from white or uncolored yarns, and thereafter dyed as a whole to obtain the desired color, or, in other words, the stocking is dip-dyed. The top of the stocking is thereafter turned down to produce the cuff in a well known manner. Stockings produced in the manner described possess many marked advantages, among which are economy in manufacture, and, if care in the selection of yarns is used, reasonable durability. On the other hand, however, the cuff is too flimsy to retain its shape, and is not sufficiently elastic to aid in supporting the stocking. Furthermore, it is frequently desirable to form the cuff of the stocking with fancy or contrasting strips which necessarily can not be obtained when the stocking is dyed as a whole.

A general object of this invention is to provide an improved stocking of the top cuff type which retains the desirable characteristics of stockings of the type heretofore in use without the disadvantages incident to either the manufacture or use thereof.

A further object of this invention is to provide a stocking in which the top cuff is

sufficiently stiff to retain its shape and at the same time elastic enough to grip the leg of the wearer and hold the stocking in place.

A further feature of the invention consists in a stocking in which the leg of the stocking is dye-dipped and the top cuff is formed of ingrained yarn.

In a further aspect, the invention provides a novel method of making a top cuff stocking.

These and other features of the invention and the novel method referred to will appear more fully from the following detailed description when read in connection with the accompanying drawing and will be pointed out in the appended claim.

In the drawing:

Figure 1 is a side elevation of a stocking constructed in accordance with the present invention;

Fig. 2 is an enlarged elevation of the cuff prior to the folding thereof;

Fig. 3 is a side elevation of a stocking showing the cuff as folded prior to attachment with the stocking leg; and

Fig. 4 is a vertical section taken through the top of a finished stocking.

Referring more particularly to the drawing, 2 indicates the main body portion or leg of the stocking which is preferably formed of silk or similar material, although the applicant does not limit the invention to the use of such material, and various other materials such as wool or cotton may be used if desired. Adjacent the top portion of the leg and knitted integral therewith is a relatively narrow strip of cotton 4. This strip 4 provides a strong backing or foundation for securing the cuff to the leg portion, and in addition serves to reduce the cost of the complete stocking. The entire leg or body portion of the stocking is formed from white or uncolored yarn and subsequently the complete leg is placed in a dye tub and dyed as a whole to any desirable shade or color.

Permanently secured to the top of the leg portion, as at 6, is a two ply top portion 8, consisting of an outer layer A and an inner layer B. The outer layer A preferably consists of a relatively wide strip 10 of cotton or other bulky material and a narrow strip 13 of silk or artificial silk. The inner layer B is formed by a relatively wide strip 14 of silk or artificial silk and a narrow strip 16 of cotton. The arrangements and

- size of the strips of silk and cotton composing the layer of the top 8 is such that when the latter is folded outwardly at a point substantially midway of its length, a cuff 18 is produced, the cotton portion of the cuff being completely covered and invisible, while the silk portions are exposed to produce the effect of an all silk stocking in the manner clearly illustrated in Figs. 1 and 4.
- 10 The top portion 8 is formed from ingrained yarn as distinguished from the white or uncolored yarn in the leg of the stocking. Ingrained yarn is yarn which has been dyed in the skein or in the thread, or 15 in other words, the individual thread is dyed prior to its formation into a fabric. In practically all of the standard processes for dyeing thread in the skein, certain loading chemicals are utilized which give to the 20 thread a hard and heavy finish. When the finished thread is thereafter knitted into a fabric, the latter is smoother and heavier in appearance than would be the case if the same yarn in an uncolored condition were 25 knitted into a fabric, and the resulting fabric thereafter dyed as a whole. The thread or yarn used in the top portion or cuff is also initially slightly heavier or coarser than the thread in the leg of the stocking, 30 although the weave is substantially the same in each case.
- 35 The use of an ingrained yarn produces a relatively heavy cuff which is sufficiently stiff to retain its initial form throughout the normal life of the stocking. Moreover, ingrained yarn is very elastic, and consequently, the cuff formed therefrom will 40 snugly grip the leg of the wearer to effectively hold the stocking in proper position upon the leg of the wearer. In addition to the stiffening effect produced by the use of

ingrained thread in the cuff, the presence of the heavy and bulky cotton layer further stiffens the cuff and facilitates the bending of the top to form the cuff.

45 A further advantage in the use of ingrained thread in the formation of the cuff of the stocking resides in the ability to produce fancy and attractive cuffs which greatly enhance the appearance of the stocking. As illustrated in the drawing, the outer surface of the cuff may be formed with a plurality of stripes 20 of any desired 50 width or color in accordance with the style or individual taste. Such a result is, of course, impossible in a dip-dyed stocking.

55 In the manufacture of a stocking in accordance with the present invention, the leg is completely formed and thereafter dyed by the dipping process. The top is then formed 60 as a separate unit by first knitting a tubular endless length of fabric such as illustrated in Fig. 2, the thread used being ingrained. The portion B is folded inwardly about a line 22 to produce the two ply top 65 8 as shown in Fig. 3. After the top is secured to the leg portion by any desirable means such as stitching, the top is folded outwardly to produce the cuff 18, the complete stocking being shown in Fig. 4.

70 Having described my invention, what I claim as new and desire to secure by Letters Patent of the United States is:

A method for making stockings, which consists in knitting the leg portion of the 75 stocking from uncolored yarn, dyeing the leg portion, knitting the top portion from ingrained yarn, and securing the top portion to the previously dyed leg portion.

70 In testimony whereof I set my signature.

WALTER J. McCLELLAND.
